MANUFACTURE OF IMIDAZOLINES CONTAINING AT LEAST 10 CARBON ATOMS

Edmund Waldmann, Klosterneuburg, and August Chwala, Vienna, Austria, assignors to I. G. Farbenindustrie Aktiengesellschaft, Frankfort-on-the-Main, Germany

No Drawing. Original application August 3, 1936, Serial No. 94,120. Divided and this application November 13, 1937, Serial No. 174,400. In Austria April 4, 1938

8 Claims. (Cl. 260—309)

The present invention relates to the manufacture of imidazolines containing at least 10 carbon atoms.

This application is a division of United States application Ser. No. 94,120, filed August 3, 1936, in the name of Edmund Waldmann and August Chwala for "Manufacture of imidazolines containing at least 10 carbon atoms".

We have found that imidazolines containing 10 aliphatic radicals of high molecular weight as substituents at the 2-carbon atom may be obtained by heating with a fatty acid or a carboxylic acid of high molecular weight to high temperatures, preferably to temperatures lying between 200° C. and 300° C., a mixture consisting on the one hand of a base having a primary amino group and a second primary or secondary amino group, which are in 1,2-position to each other, the two carbon atoms in 1,2-position being linked 15 by a single bond, and on the other hand a salt of such base formed from a strong acid.

Suitable bases having a primary amino group and a second primary or secondary amino group in 1,2-position to each other are ethylene-diamine; products such as diethylene-triamine, triethylene-tetraethylene-pentamine; homologues of ethylene-diamine such as 1,2-propylene-diamine, 2,3-butylenediamine, N-methyl-ethylene-diamine.

30 Suitable strong acids for forming the salts are in particular mineral acids, such as hydrochloric acid, hydrobromic acid, sulfuric acid, and the like.

Suitable fatty acids of high molecular weight are in general aliphatic acids containing more 35 than 8 carbon atoms, for instance, caprylic acid, lauric acid, stearic acid, palmitic acid, oleic acid, also mixtures of these acids obtainable by saponifying natural fats like olive oil, tallow, palm oil; also cycloaliphatic acids such as naphthenic acids 40 and the like.

Instead of the fatty acids there may be used suitable derivatives thereof such as esters, amides, anhydrides or halides; according to the selection of the derivative to be used, the simultaneous use of the free base or the salt of the base may, if desired, be omitted, for in the case of halides the suitable mixtures leading to the desired result are formed, due to the mineral acid becoming free, in the course of the acylation.

50 Quite generally, the new process consists in heating with a product selected from the group consisting of fatty acids of high molecular weight and the salts, amides, halides and esters thereof, a mixture consisting on the one hand of a base which is substituted at two carbon atoms

adjacent to each other by an amino group each, of which amino groups one contains two hydrogen atoms and the other at least one hydrogen atom, and on the other hand of a salt of such base with a strong acid, the heating being carried out at a high temperature.

The procedure may also be such that first of all the salt of the mono-acyl compound is prepared. The process then consists in heating to a high temperature a salt formed from a strong acid and such a diamine mono-acylated with a fatty acid of high molecular weight, in which the two amino groups are bound to two carbon atoms adjacent to each other, one of which amino groups containing two hydrogen atoms and the other at least one hydrogen atom.

In the preferred mode of operating, the mixture made in accordance with the invention is heated to a temperature of 250° C.—290° C. If, for example, there is used a quantity of lauric acid, ethylene-diamine and ethylene-diamine hydrochloride, the hydrochloride which forms a sediment dissolves very quickly in this interval of temperature, even with only gentle stirring, and at the same time causes formation of the undecyl-imidazoline hydrochloride. This reaction may also be conducted at a temperature lower than 250° C. by heating for a longer period. The use of a vacuum during the second half of the condensation is useful.

When the condensation to the imidazoline derivative starts from a mixture of fatty acid amine and amine hydrochloride, the three components of the mixture are advantageously selected so that for 1 mol of the fatty acid or its derivative there are at least 1 mol each of the diamine and the salt-like bound mineral acid. In using one mol of lauric acid, therefore, there should be $\frac{1}{2}$ mol of ethylene-diamine and $\frac{1}{2}$ mol of ethylene-diamine hydrochloride, corresponding with the equation:

and there is obtained the hydrochloride of undecylimidazoline.

If as the lauric acid derivative there is chosen the dilaurylethylene-diamine which for one mol of lauric acid already contains $\frac{1}{2}$ mol of ethylene-diamine in a bound state, one mol of this diacyl body is heated with 1 mol of ethylene-diamine hydrochloride at about 250° C.—290° C.

there is obtained the reaction in the sense of the following equation:

the product being again undecylimidazoline hydrochloride in approximately quantitative yield.

- 10 If, however, the parent material is the mono-lauroyl-ethylene-diamine hydrochloride which already contains in itself per 1 mol of fatty acid 1 mol of ethylene-diamine and 1 mol of hydrochloric acid, it suffices to heat this hydrochloride 15 by itself to about 250° C.-300° C. in order to obtain an excellent yield of the hydrochloride of undecylimidazoline. This reaction can also be carried out with the other mono-acyl derivatives which are obtained from the diamines and 20 the fatty acids of high molecular weight mentioned in paragraphs 2 and 4 of this specification.

- Under the effect of the amine salt, particularly 25 the hydrochloride, one finds at comparatively high temperature of reaction evidently an elimination of the acid amide at first formed (as may be seen particularly clearly from the example of dilauroyl-ethylenediamine) and then a combination of the eliminated material directly to the imidazoline hydrochloride. Philipps (Journal of the Chemical Society of London, 1928, page 2393 and following; Chemisches Zentralblatt 1928, vol. 2, page 2466) is of opinion that 30 the formation of benzimidazoles or imidazolines from the acyl derivatives of the corresponding diamines by boiling with hydrochloric acid occurs of itself in such a manner that the acid amide is first saponified and the eliminated portion united directly to the benzimidazol or imidazoline.

- These imidazolines of high molecular weight 40 in the form of their salts are freely soluble in water; solutions foam and have good capillary active properties. They may be used with advantage for improving dyeings on vegetable fibers.

- 45 Sulfo groups may be introduced in their molecules by the methods which have become known from French Specification No. 796,917. These imidazoline sulfonates of high molecular weight are also valuable as wetting, foaming, washing, 50 emulsifying and dispersing agents. They are valuable as assistants in the textile industry.

The following examples serve to illustrate the invention, the parts being by weight:

- 55 (1) Into a stirring vessel provided with a thermometer and an inverted condenser there are charged

	Parts
Stearic acid	284
Ethylene-diamine hydrochloride	93
Ethylene-diamine hydrate	56

- The mixture is heated, while stirring, to 120° C. and the temperature is raised within 90 minutes to 185° C., whereby between 170° C. and 185° C. a small proportion of a clear liquid distils (ethylene-diamine hydrate and water). The mixture is now heated within 30 minutes to 230° C. and then within 15 minutes to 290° C. The mass is kept for a short time at this temperature, which 70 may be raised to 300° C., until a sample of the mass, tested with water, shows that it is soluble in water to a clear solution; the heating is then interrupted and the mass cooled. The brownish 75 mass, which is crystalline when cold, consists

almost exclusively of heptadecylimidazoline hydrochloride.

A free base may be separated in known manner by dissolving the hydrochloride with water and liberating the base with an alkali-hydroxide 5 which can then be directly filtered or extracted by means of benzene. For further purification the product may be crystallized from a mixture of 3 parts of methyl alcohol and 1 part of water, whereby 2-heptadecylimidazoline is obtained in 10 crystalline scales melting at 94° C.-95° C.

(2) In an apparatus such as is described in Example (1) there is heated a mixture of:

	Parts
Lauric acid	130
Ethylene-diamine hydrate	40
Ethylene-diamine hydrochloride	60

in the manner described in the same example. As soon as a sample of the mass is clearly soluble 20 in water, the heating is interrupted. On cooling, the mass solidifies in crystalline form; it consists of 2-undecylimidazoline hydrochloride. The base liberated in the usual manner from this salt may be purified by recrystallization from 25 alcohol of 50 per cent. strength, whereby it is obtained in the form of colorless laminae which melt at 82° C.

(3) In an apparatus such as is described in Example (1) there is heated to 180° C. a mix- 30 ture of:

	Parts
Oleic acid	140
Ethylene-diamine hydrate	15

the mass which at first is somewhat foamy boils 35 finally gently as soon as the water has been distilled. After cooling to 120° C. there are added another 15 parts of ethylene-diamine hydrate and heating is renewed to 180° C. 37.5 parts of ethylene-diamine hydrochloride are now added, 40 whereupon the temperature of the mass is raised to 280° C. within 15 minutes and kept there for 10 minutes. The mass is then allowed to cool to 120° C., another 10 parts of ethylene-diamine 45 hydrate are added, and the mixture is heated within 20 minutes to about 300° C., and kept at this temperature until a sample dissolves clearly in water, whereupon the heating is immediately interrupted.

In this manner there is obtained the 2-hepta- 50 decenylimidazoline hydrochloride in the form of a semi-solid brownish mass which dissolves clearly in water with the formation of a strongly foaming solution from which the base may be isolated in the usual manner.

	Parts
Oleic acid ethyl ester	10
Ethylene-diamine hydrate	2
Ethylene-diamine hydrochloride	3

are heated together in the manner described in Example 1, save that the temperature of the mass for the saponification of the ester is allowed to remain for some time (about 5-10 minutes) at 120° C.-130° C. The aqueous solution 65 of the heptadecenylimidazoline hydrochloride is treated with some active carbon and the free base is liberated by means of caustic soda; it is obtained in very good yield.

(5) 8.5 parts of N-N-di-lauroylethylene-di- 70 amide are heated with 3.3 parts of ethylene-diamine hydrochloride in an open flask, while stirring, in such a manner that after 5-10 minutes the mixture has a temperature of about 270° C.-280° C. The heating is continued for 75

another 10 minutes to 280° C.-290° C., whereby the greater quantity of the hydrochloride passes into solution. A sample then dissolves clearly in water.

5. Caustic soda solution precipitates from the aqueous solution the undecylimidazoline which is the product of reaction in approximately quantitative yield.

(6) 10 parts of mono-lauroylethylene-diamine hydrochloride are heated for 5-10 minutes to 260° C.-280° C. and then for a further 5-10 minutes to 285° C.-295° C. The hydrochloride of the undecylimidazoline is thus formed. A similar result is obtained by substituting the corresponding hydrobromide or sulfate for the mono-lauroylethylene-diamine hydrochloride, or by using instead of the mono-lauroyl-ethylene-diamine hydrochloride a derivative acylated with another fatty acid of high molecular weight, such as, for example, the mono-stearoyl-, the mono-oleoyl-, the mono-palmitoyl-, the mono-capryloylethylene-diamine hydrochloride, or finally by using the corresponding 1,2-propylene-diamine or 2,3-butylene-diamine derivatives.

25. We claim:

1. Process for the manufacture of 2-substituted imidazolines which comprises heating to a high temperature a salt formed from a strong acid and such a diamine mono-acylated with a fatty acid having at least 8 carbon atoms, in which the two amino groups are bound to two carbon atoms adjacent to each other and linked by a single bond, one of which amino groups contains two hydrogen atoms and the other at least one hydrogen atom.

2. Process for the manufacture of 2-substituted imidazolines which comprises heating to temperatures lying between 200° C. and 300° C. a salt formed from a strong acid and such a diamine monoacylated with a fatty acid having at least 8 carbon atoms, in which the two amino groups are bound to two carbon atoms adjacent to each other and linked by a single bond, one

of which amino groups contains two hydrogen atoms and the other at least one hydrogen atom.

3. Process for the manufacture of 2-substituted imidazolines which comprises heating to temperatures lying between 200° C. and 300° C. a salt formed from a strong acid and such a diamine monoacylated with a fatty acid containing from 10 to 18 carbon atoms, in which the two amino groups are bound to two carbon atoms adjacent to each other and linked by a single bond, one of which amino groups contains two hydrogen atoms and the other at least one hydrogen atom.

4. Process for the manufacture of 2-substituted imidazolines which comprises heating to high temperatures lying between 200 and 300° C., a salt formed from a strong acid and ethylene-diamine mono-acylated with a fatty acid containing from 10 to 18 carbon atoms.

5. Process for the manufacture of 2-substituted imidazolines which comprises heating to temperatures lying between 250° C. and 300° C. the hydrochloride of ethylene-diamine mono-acylated with a fatty acid containing from 10 to 18 carbon atoms.

6. Process for the manufacture of the 2-heptadecylimidazoline consisting in heating to temperatures lying between 250° C. and 300° C. the hydrochloride of the ethylene-diamine mono-acylated with stearic acid.

7. Process for the manufacture of the 2-heptadecenylimidazoline consisting in heating to temperatures lying between 250° C. and 300° C. the hydrochloride of the ethylene-diamine mono-acylated with oleic acid.

8. Process for the manufacture of the 2-undecyl-imidazoline consisting in heating to temperatures lying between 250° C. and 300° C. the hydrochloride of the ethylene-diamine mono-acylated with lauric acid.

EDMUND WALDMANN.
AUGUST CHWALA.
